AUTOMOBILE TRIM

Aloysius J. Kaminski, Detroit, Mich., assignor to Chrysler Corporation, Highland Park, Mich., a corporation of Delaware

Application August 13, 1949, Serial No. 4,469

Term of patent 7 years

(Cl. D14—6)

To all whom it may concern:

Be it known that I, Aloysius J. Kaminski, a citizen of the United States, residing in the city of Detroit, county of Wayne, and State of Michigan, have invented a new, original, and ornamental Design for an Automobile Trim, of which the following is a specification, reference being had to the accompanying drawing, forming part thereof, in which:

Fig. 1 is a top plan view of an automobile trim showing my new design;

Fig. 2 is a side elevation thereof, and

Fig. 3 is a vertical section taken on the line 3—3 of Fig. 2.

I claim:

The ornamental design for an automobile trim, substantially as shown.

ALOYSIUS J. KAMINSKI.
